UNITED STATES PATENT OFFICE

93,283

DESIGN FOR A PAIR OF SPECTACLES

Chester C. Norris, Atlanta, Ga.

Application December 4, 1933, Serial No. 49,938

Term of patent 14 years

To all whom it may concern:

Be it known that I, CHESTER C. NORRIS, a citizen of the United States, whose post-office address is 110 Whitehall Street, S. W., Atlanta, Georgia, have invented a new, original, and ornamental Design for a Pair of Spectacles, of which the following is a specification, reference being had to the accompanying drawing, forming part thereof.

Fig. 1 is an enlarged front elevational view of a lens shaped in accordance with my invention.

Fig. 2 is a top view of the lens illustrated in Fig. 1.

Fig. 3 is a view in perspective of a pair of rimless glasses assembled with lenses embodying my invention.

The dominant feature of my design resides in the ornamental effect produced by constructing a pair of spectacles having lenses with equal sides at the top and relatively small angles there, along with a somewhat narrowed bottom section.

I claim:

The ornamental design for a pair of spectacles, as shown and described.

CHESTER C. NORRIS.
